(57) **CLAIM**

The ornamental design for a connector for a patient ventilating and aspirating system, as shown and described.

DESCRIPTION

FIG. 1 is a perspective view of the connector for a patient ventilating and aspirating system;

FIG. 2 is a top plan view of the connector for a patient ventilating and aspirating system;

FIG. 3 is a left side elevational view of the connector for a patient ventilating and aspirating system;

FIG. 4 is a front elevational view of the connector for a patient ventilating and aspirating system;

FIG. 5 is a right side elevational view of the connector for a patient ventilating and aspirating system; and,

FIG. 6 is a bottom plan view of the connector for a patient ventilating and aspirating system.

The rear elevational view of the connector for a patient ventilating and aspirating system is the mirror image of the front elevational view of the connector for a patient ventilating and aspirating system shown in FIG. 4.

The broken lines in the drawings show environmental structure that form no part of the design to be patented.
